US0D1030146S

(12) **United States Design Patent** (10) **Patent No.:** **US D1,030,146 S**
(45) **Date of Patent:** **** Jun. 4, 2024**

(54) **NAIL TRIMMING DEVICE**

(71) Applicant: **Church & Dwight Co., Inc.**, Princeton, NJ (US)

(72) Inventors: **Aaron Szymanski**, Thomaston, CT (US); **Lana Rascionato**, Totowa, NJ (US)

(73) Assignee: **Church & Dwight Co., Inc.**, Princeton, NJ (US)

(**) Term: **15 Years**

(21) Appl. No.: **29/752,265**

(22) Filed: **Sep. 25, 2020**

(51) **LOC (14) Cl.** **28-03**

(52) **U.S. Cl.** USPC **D28/59**

(58) **Field of Classification Search**

USPC 132/73.6, 75; D28/58, 59, 62
CPC A45D 29/007; A45D 29/02; A45D 29/05;
A45D 29/06; A45D 29/18

(57) **CLAIM**

The ornamental design for a nail trimming device, as shown and described.

DESCRIPTION

FIG. 1 is a front perspective view of an embodiment of a nail trimming device of the present invention showing our new design;

FIG. 2 is a front view thereof;

FIG. 3 is a rear view thereof;

FIG. 4 is a side view thereof;

FIG. 5 is another side view rotated 180 degrees relative to FIG. 4;

FIG. 6 is a top view thereof; and,

FIG. 7 is a bottom view thereof.

The broken lines shown herein depict portions of the nail trimming device and form no part of the claimed design.

1 Claim, 4 Drawing Sheets
